UNITED STATES PATENT OFFICE.

FRANCIS DE FONTES, OF BALTIMORE, MARYLAND.

HEAD-REST.

No. 830,826.

Specification of Letters Patent.

Patented Sept. 11, 1906.

Application filed December 30, 1905. Serial No. 294,010.

To all whom it may concern:

Be it known that I, FRANCIS DE FONTES, a citizen of the United States, residing at Baltimore, in the State of Maryland, have invented 5 certain new and useful Improvements in Head-Rests, of which the following is a specification.

This invention relates to head-rests of that class which are supported on a standard that 10 is vertically adjustable with respect to the back of the chair and which are also pivoted at the top of said standard, so as to be capable of tilting in a back and forward direction; and the object of this invention is to combine 15 with the mechanism of such a head-rest a spring which will operate to allow of a yielding movement of the head-rest back and forward on the pivot after the head-rest has been adjusted approximately to a position to suit 20 the individual.

The invention is illustrated in the accompanying drawings, in which—

Figure 1 is a side elevation of the head-rest, a portion being shown in section. Fig. 2 is a 25 vertical section of the head-rest and standard, the section being taken on the line 2 2 of Fig. 3. Fig. 3 is a top view showing on a larger scale the segment-arm and the spring-supporting plate which is pivoted, this view 30 illustrating those parts below the line 3 3 of Fig. 1. Fig. 4 is a top perspective view of the plate that is rigidly attached to the under side of the head-rest and carries the ears by which the latter is pivoted. Fig. 5 is a 35 perspective view of the spring-latch. Fig. 6 is an inverted or bottom view of one end of the pivoted spring-supporting plate. Fig. 7 shows a bottom view of the guide-bar below the spring-latch.

40 The letter A designates the head-rest proper, and B the supporting-standard, having a straight rack c, by which the standard and head-rest may be vertically adjusted relative to the back of the chair, which latter 45 is not shown in the drawings.

The letter h designates the pivots, by which the head-rest may be tilted in a back or forward direction.

At the under side of the head-rest are two 50 ears d, which are integral with a plate d', which is rigidly attached to the head-rest. These ears and the plate d' are shown separately in Fig. 4.

The upper end of the standard B has a rigid 55 arm e projecting rearward from the head-rest, and this arm on its outer vertical edge is pro-

vided with a segment-shaped rack e', having teeth e''. The segment-rack has at its top a projecting-tang f, and at its bottom a projecting tang f''. In the present instance the arm 60 with the segment-rack e' has at its base a cross-piece or T-piece e'', which projects down on the side of the standard B and is secured thereto by a screw e'.

A plate G is pivoted to the same pivots h, 65 on which the ears d of the head-rest tilt. This plate projects rearward from the pivots and supports the spring or springs I, interposed between it and the head-rest. In the present instance this plate G has a T-shaped slot 70 j, which takes over the upper end of the standard and arm with the segment-rack, as shown in Fig. 3.

The pivoted plate G carries at its free end a latch k, separately seen in Fig. 5. The 75 latch is shown in the present instance at the bottom side of the pivoted plate and one end of the latch has a hole k' and is attached to the plate by a pivot-pin k'', inserted through said hole k' and also through a hole k''' in the 80 pivoted plate. The latch has a thumb-piece k'' at its free end to facilitate shifting. It also has on outer edge a flange or lug l. This pivoted latch k engages the teeth e'' on the segment-rack and serves to sustain the piv- 85 oted plate G at any desired elevation. A guide-bar m is secured on the under side of the pivoted plate and below the latch and is seen separately in Fig. 7 and in broken lines in Fig. 3. This bar rests against two circular 90 bosses n n' and is secured by pins or screws in holes n'', formed in said bosses. A lug o is also on the under side of the pivoted plate adjacent one of the bosses n. A steel-wire spring p is wound once around the circular 95 boss n, and the short end of the wire is held by being bent in the space between the boss n and the lug o. The long end of the wire spring extends from the said boss n alongside of the outer edge of the latch k and rests on the 100 flange or lug l, as shown in broken lines in Fig. 3. This lug keeps the wire from slipping off said edge. The effect of the wire spring p is to keep the pivoted latch k pressed into engagement with the teeth e'' on the segment- 105 rack. The free end of the pivot-plate G is adjustable up and down on the segment-rack and is limited in its movement by the top and bottom tangs f f'' on the stationary arm e.

As the guide-bar m rests against the two 110 bosses n n', which are on the under side of the pivoted plate G, a space is formed between

said bar and plate, in which the pivoted latch *k* may swing freely.

The head-rest *A* comprises a block with a suitable pad *q* on top, and in its lower side the

5 block has a slot *r* to receive the stationary arm *e* when the head-rest is tilted back. The lower side of the head-rest also has a socket *s*, which receives the upper end of the spiral spring *I*, the lower end of said spring being

10 supported by the pivoted plate *G* and taking over a lug *t* on the upper surface of said plate.

It is obvious that either one or two spiral springs *I* may be used between the pivoted plate *G* and pivoted head-rest *A*.

15 By the construction and combination of parts here described the head-rest, after being adjusted to a position that will suit the individual, will have a yielding movement backward and forward on its pivots *h*.

20 Having thus described my invention, what I claim as new, and desire to secure by Letters Patent, is—

1. The combination of a supporting-standard; a head-rest pivoted to tilt back and forward on said standard; a pivoted plate below the head-rest and with its free end movable up and down, and a spring interposed be-

tween the said pivoted plate and pivoted head-rest whereby the head-rest after it has been adjusted may have a yielding movement back and forward on its pivot.

2. The combination of a supporting-standard having a stationary arm provided with a segment-shaped rack; a head-rest pivoted to tilt back and forward on said standard; a pivoted plate below the head-rest and with its free end movable up and down, and carrying a latch which engages said rack; and a spring interposed between the said plate and head-rest.

3. The combination of a supporting-standard having a stationary arm provided with a segment-shaped rack; a head-rest and a plate below the head-rest but independent of the head-rest and both pivoted on the same pivots; a latch attached to the pivoted plate and engaging the said rack; and a spring interposed between the said plate and head-rest.

In testimony whereof I affix my signature in presence of two witnesses.

FRANCIS DE FONTES.
